UNITED STATES PATENT OFFICE

JOSEPH H. ALLEN, OF CHICAGO, ILLINOIS, ASSIGNOR TO INLAND GLASS WORKS, INC.,
OF CHICAGO, ILLINOIS

DESIGN FOR A LAMP GLOBE

Application filed January 26, 1931. Serial No. 38,444. Term of patent 14 years.

To all whom it may concern:

Be it known that I, JOSEPH H. ALLEN, a citizen of the United States, residing at Chicago, in the county of Cook and State of Illinois, have invented a new, original, and ornamental Design for Lamp Globes, of which the following is a specification, reference being had to the accompanying drawings, forming a part thereof.

Figure 1 is a side elevation of a lamp globe embodying my new design.

Figure 2 is a side elevation of a lamp globe embodying my new design, the globe being rotated through a 90° angle about an axis from the position shown in Figure 1.

Figure 3 is a perspective three-quarter (3/4) bottom view of the lamp globe.

I claim:
The ornamental design for a lamp globe as shown.

JOSEPH H. ALLEN.
